ENERGY-METER FOR ALTERNATING ELECTRIC CURRENTS.

1,291,110.

Specification of Letters Patent.

Patented Jan. 14, 1919.

Application filed March 24, 1917. Serial No. 157,071.

To all whom it may concern:

Be it known that we, CHARLES PERDRISAT and ALBERT PELOUX, citizens of Switzerland, residing at Geneva, Canton of Geneva, in 5 the Confederation of Switzerland, have invented certain new and useful Improvements in Energy-Meters for Alternating Electric Currents, of which the following is a specification.

10 This invention relates to an energy meter for alternating electric current.

It operates, like other known energy meters for alternating electric current, according to the principle of the Ferraris rotating field, and, like them, comprises a magnetic frame which includes a middle part and two end parts, one of which carries a current winding and the other a pressure winding, together with a piece of laminated iron constituting a shunt for the magnetic circuit of the current winding and serving to produce the phase displacement between the pressure and current fluxes. But it is distinguished therefrom by the fact 25 that one of the extremities of the frame that carries the pressure winding, being bent, exhibits at least one branch which is directed away from the middle part of the frame, in such a way that the piece forming the shunt and facing the latter can be displaced for the purpose of regulating the phase displacement without any other part of the meter but this piece having to be touched.

The accompanying drawing shows one 35 constructional form of the meter and two variations thereof, the whole being given diagrammatically by way of example.

Figures 1 and 2 are two elevations, taken at 90° from one another, of this constructional form.

Fig. 3 shows a detail of it.

Figs. 4 and 5 relate to the variations.

According to Figs. 1 and 2 the magnetic frame of the meter comprises an element A 45 constituting its middle part, having the shape of a C and being placed in a vertical plane in such a way that its central branch is vertical. On to one of the extremities of the element A is fitted an element M, which 50 constitutes one of the end parts of the

frame, and is angular or bent so as to have the shape of an L, and the vertical branch of which carries a pressure winding K connected by conductors Q, R to the two conductors N, O, to which the devices supplied 55 with the current, lamps P for instance, are connected. To the other end of the element A is fixed a U-shaped element C, forming the other end part of said frame, and arranged in a vertical plane at right angles to 60 the vertical plane in which A is located. The two vertical limbs of the element C are provided with two portions L, L' of a current winding inserted in the conductor N. The element M is provided with lateral 65 angle pieces or elements E, E' extending right over said vertical limbs and serving to close the magnetic circuit of the current winding. Finally, between the lower end of the element A and the element C is arranged an element D, which is T shaped and the middle branch of which has a horizontal portion passing between the two vertical branches of the piece C, almost at the level 70 of the upper extremities of the latter. 75

The elements A, M, C are of laminated iron, while the elements D, E, E' are of thin sheet iron.

The movable system of the meter comprises a solid metal disk F, rotating between 80 the element M and the angle-pieces E, E' on one hand, and the upper ends of the branches of the element C and the horizontal part of the element D on the other hand. The disk is fixed to a vertical shaft G actuating the counter of the meter in a manner which the drawing does not show. The rotation effected by this disk F is braked by means of a permanent horse-shoe magnet S, between the two branches of which F passes. 85 90

The magnetic flux produced by the pressure winding K traverses the magnetic circuit constituted by the elements M, A, C, E and E' or D, M. But in order to obtain the rotating field necessary for the working of 95 the meter according to the principle of Ferraris it is requisite that said pressure winding flux should undergo a phase displacement of 90° with respect to the magnetic flux produced by the current winding L—L'. 100

To this end, a part of the above magnetic circuit, the element M, is shunted by a shunting piece B, made of laminated iron, having the form of an L and placed in such a way that its two extremities face the inner surfaces of the element M, which is also shaped like an L, the horizontal branch of which is directed away from the piece A. One of the extremities of the shunting piece 10 is in contact with the face of M adjacent thereto, while the other is always at a certain distance from the surface of M that faces it. The adjustment of the intensity of the shunting and consequently that of the 15 phase displacement between the pressure and current fluxes is effected by varying the air gap between the element M and piece B. For that purpose the latter is fixed by a screw T which passes into an elongated hole 20 V. (Fig. 3) which it presents to a place U attached to the element A. The major dimension of the hole V is vertical, which enables the element B to be raised or lowered with respect to the piece M.

25 Thanks to the selected arrangement of the elements M and B, the adjustment of the phase displacement by means of the magnetic shunt is effected in a simple and practical manner by displacing the second without having to touch any other part of the 30 meter but that.

According to Fig. 4 the piece B and element M are also L-shaped, but the first is of such dimensions that its inner surfaces face 35 the rectangular surfaces that are at the extremities of the second. The element M may also be C-shaped (Fig. 5), having both its end branches directed away from the element A. In this case the piece B has the 40 shape of an I, and the shunt magnetic circuit comprises two air gaps.

The means enabling the piece B to be displaced without touching the other parts of the meter may differ from those illustrated 45 in the drawing and described. The branch or branches of the element M, while still being directed away from the element A, may not be in the same plane as the latter.

We claim as our invention:

50 1. In a meter for alternating electric currents operating on the principle of the Ferraris rotating field, a magnetic frame having a central and two end members, a current winding on one end member, a pressure 55 winding on the other end member which is angular and has a branch directed away from the central member of the frame, and an adjustable member coöperating with said angular member to provide a shunt path for 60 the magnetic flux set up by the pressure winding.

2. In a meter for alternating electric currents operating on the principle of the Fer-

raris rotating field, a magnetic frame having a central member placed vertically, an 65 angular shaped end member secured to one extremity of the frame with a branch directed away from the central vertical member of the frame, a pressure winding on the said angular shaped end member, an end 70 member connected to the other extremity of the frame, a current winding on the said second end member, and an adjustable member coöperating with said angular shaped end member to provide a shunt path for the 75 magnetic flux set up by the said pressure winding.

3. In a meter for alternating electric currents operating on the principle of the Ferraris rotating field, a magnetic frame having a vertically placed central member, an L-shaped end member secured adjacent one extremity of the said frame and having a branch thereof directed away from the central vertical portion of the frame, a pressure 80 winding on the said L-shaped end member, a U-shaped end member secured to the other extremity of the vertically placed frame, a current winding on the legs of the said U-shaped end member, and an adjustable 85 member coöperating with said L-shaped end member to provide a shunt path for the magnetic flux set up by the said pressure winding.

4. In a meter for alternating electric currents operating on the principle of the Ferraris rotating field, a magnetic frame having a central vertically placed member, an L-shaped end member, the end of its longer branch secured adjacent the extremity of the vertically placed frame with its shorter branch directed away from the central portion of the frame, a pressure winding on the longer branch of the said L-shaped member, a U-shaped end member secured adjacent the other extremity of the said frame, members associated with the L-shaped member for completing the magnetic circuit in the U-shaped member, and a member adjustable in the magnetic frame and coöperating with 100 said L-shaped end member to provide a shunt path for the magnetic flux set up by the pressure winding.

5. In a meter for alternating electric currents operating on the principle of the Ferraris rotating field, a magnetic frame having a central vertically placed member, an L-shaped end member, the end of its longer branch secured adjacent the extremity of the vertically placed frame with its shorter 115 branch directed away from the central portion of the frame, a pressure winding on the longer branch of the said L-shaped member, a U-shaped end member secured adjacent the other extremity of the said frame, members 120 associated with the L-shaped member for

completing the magnetic circuit in the U-shaped member, a T-shaped member associated with the said U-shaped end member, and a member adjustable in the magnetic frame and cooperating with said L-shaped end member to provide a shunt path for the magnetic flux set up by the pressure winding.

In testimony whereof we have affixed our signatures in presence of two witnesses.

CHARLES PERDRISAT.
ALBERT PELOUX.
